WORK SUPPORTS FOR SHOE MACHINES

Donald Cecil Pilz, Leicester, England, assignor to United Shoe Machinery Corporation, Flemington, N.J., a corporation of New Jersey

Filed Dec. 9, 1958, Ser. No. 779,236

Claims priority, application Great Britain Feb. 7, 1958

9 Claims. (Cl. 12—86.7)

This invention relates to shoemaking machines and more particularly to machines in which operations are performed on shoe parts and/or shoes in various stages of manufacture which are mounted on and firmly clamped to a last. The invention is particularly directed to a machine for clamping a last with a shoe part or parts firmly attached thereto in a jack for presentation to an operating tool.

One of the first operations in the fabrication of shoes which requires a shoe part to be clamped to a last is the shaping of an insole to the contours of the last. The insole is generally cut from flat stock and usually in a horizontal plane with the result that when the insole is tacked to the bottom of a last it sometimes does not precisely register with the last which has many curvatures on and about its bottom surface. To insure, therefore, a correct size insole for a particular last, it is a common practice initially to cut the insole somewhat longer at its heel end than the dimension of the last for which it is intended and when the insole has been tacked to the last, it is then trimmed to register precisely with the periphery of the last bottom. It is desirable that the finished shoe have a smooth continuous curve from the upper edge of the shoe at the heel end to its heel seat portion. For this reason it is frequently desirable to bevel the edge of the insole at an angle such that the curve represented by the back of the last and the contour of the periphery of the insole are substantially continuous. When the insole is made of leather it is a relatively simple operation to trim and bevel its edge by the use of a rotary cutter. However, in recent years it has become a practice in shoe manufacturing to reinforce insole's with hard fibrous substances, resulting in a more difficult task for an operator and for the cutting tools of machines previously used to trim and bevel leather insoles. Furthermore, difficulty also arises from the fact that the resistance offered by the hard fibrous substance to the action of the trimming tool or cutter tends to displace the insole relatively to the last bottom in spite of tacks which are inserted to prevent such relative movement. Clamping means for securing the insoles to the last bottom have hitherto been available for this operation but have not been of a nature to hold the insole firmly against such displacement, nor have such clamps been convenient to operate particularly when a large range of sizes of shoes are being made. In numerous other shoe manufacturing operations it is necessary to clamp shoe parts or partially fabricated shoes firmly on their last to assure accurate presentation to operating tools.

Accordingly, it is an object of this invention to provide a machine for operating on a shoe part mounted on a last, the machine having convenient clamping means exerting sufficient force to hold the part in engagement with the last against displacement relatively thereto as the machine operates on the shoe part.

A second object of this invention is to provide a shoe machine having clamping mechanism which is simple to

2

operate and which does not require strenuous effort on the part of the operator to effect such clamping.

Another object of this invention is to provide a shoe machine having clamping mechanism which is hydraulically operated and which automatically compensates for fluid pressure variations in order to effect a constant clamping pressure.

Another object of the invention is to provide a machine for trimming reinforced insoles, the machine having convenient work clamping means of sufficient strength to hold the insole against displacement relatively to the last bottom with constant pressure as the trimming cutter acts on the reinforcing material.

In a copending application Serial No. 630,940, filed December 27, 1956, in the name of B. J. M. Murphy (now U.S. Patent No. 2,892,199, granted June 30, 1959), there is disclosed a machine for clamping shoe parts against a last positioned in a jack for presentation to an operating tool. In many respects the present invention is similar to the Murphy machine but it is considered to be an improvement thereover. The Murphy machine is an insole trimmer having a cutter and an operator actuated jack mounting a hydraulically operated clamping mechanism comprising a first clamp and a second clamp movable relatively thereto by pressurized fluid. By this clamping mechanism a last with an attached insole may be firmly gripped between the clamps while being presented to the cutter. Hydraulic operating fluid is supplied to the clamping means from a treadle operated fluid pump comprising piston-cylinder mechanism. In order to compensate for variations in pressure of the operating fluid the piston-cylinder mechanism is provided with adjustable means to permit movement of the cylinder relatively to the piston to vary the volume within which the operating fluid is compressed.

In accordance with the various features of the present invention, although the same clamping means are provided, the treadle operated piston and cylinder mechanism is eliminated and is replaced by a more accurate fluid pressure regulating mechanism including a fluid pump for directing pressurized operating fluid to the clamps and a valve for automatically controlling the pressure of the operating fluid. A manually operated lever is conveniently mounted on the jack within the grasp of the operator while he is moving the jack to present the work to the tool. Through appropriate linking means the lever actuates the control valve which is located remotely from the jack. The valve which is associated with the fluid pump includes extremely sensitive pressure relief valve means to compensate for variations in pressure of the operating fluid thereby to maintain the pressure at the clamping means automatically at a substantially constant value.

The above and other features of the invention including various novel details of construction and combinations of parts will now be more particularly described with reference to the accompanying drawings and pointed out in the claims.

In the drawings,

Fig. 1 is a front elevation partly broken away with portions shown in section of an insole trimmings machine embodying the invention;

Fig. 2 is a detail view on an enlarged scale partly in section of an operative portion of the machine shown in Fig. 1 with the parts in work clamping positions; and

Fig. 3 is a detail view similar to Fig. 2 with the parts in normal or inoperative positions.

The apparatus illustrated in the drawings is an insole trimming machine similar to that disclosed in the above-mentioned Murphy patent and adapted to trim and bevel the peripheral portions of an insole secured to a

last, the insole and last being firmly clamped together during the trimming operation. It will be understood that this illustrative machine is selected for description of the invention and is not to be construed as a limitation thereof. The shoe part need not necessarily be an insole nor the tool a trimming cutter. Referring to Fig. 1, which shows the front of the machine as viewed by an operator presenting a shoe thereto, the machine comprises a base 2 with a frame 4 mounted thereon in which is journaled a horizontally extending shaft 6 that carries a tool in the form of a trimming and beveling cutter 8. Connected to the frame 4 is a C-shaped work supported jack 10 of the type illustrated in the Murphy patent and which forms no part of the present invention. The jack 10 carries clamping means comprising a first rotatable clamp 12 and a second rotatable clamp 14 movable bodily relatively thereto in axial alignment therewith.

The second clamp 14 is formed on the end of a spindle constituting a piston movable within a horizontal cylinder 15 considered part of the clamping member and mounted on the jack 10. Connected to the cylinder is the upper portion of a flexible pipe or fluid conduit 16. The cylinder 15 forms that portion of the jack which is normally grasped by the operator to assist in guiding the edge of the work piece clamped to a last in the jack to the trimming and beveling cutter 8. Normally, the cylinder 15 would be grasped by the operator's left hand while the last with the work attached is rotated by the right hand of the operator in the jack relatively to the cutter.

Manually operated control means in the form of a lever 17 is mounted on the cylinder 15, hereinafter known as the clamping cylinder, in position to be readily grasped by the operator as his hand encircles it. The lever 17 which is pivoted on the clamping cylinder is connected to the core of a sheathed Bowden cable 18, which, along with the fluid conduit 16, passes downwardly of the machine. The cable and conduit are both connected in a manner hereinafter to be described, to a fluid control valve 20 mounted in a hydraulic fluid reservoir 21 located within the base 2 of the machine. Also located within the reservoir 21 and connected to the valve 20 is a fluid pump 24.

The fluid control valve 20 comprises a main valve block 26 secured to the side of the reservoir 21 and provided with an inlet passageway 28 which communicates with the pump 24 by way of a fitting 30 and a pipe 32. The valve 20 also communicates by way of a passage 34 and fitting 36 with the fluid conduit 16 leading to the clamping cylinder 15. Another passageway 38 in the valve block 26 communicates directly with the interior of the reservoir 21. The level of fluid within the reservoir is maintained at a sufficient height H whereby the valve 20 is completely submerged at all times. Still another passageway 40 in the block 26 communicates with a relief valve 42.

A sleeve 44 is fitted in the interior of the block 26 and together with the block forms the body of the valve 20 also known as the valve cylinder. A constant diameter bore 45 is formed in the interior of the sleeve 44 and a series of co-planar radially spaced passageways 33, 35 and 37 each leading to an annular recess, place the bore in communication with the passageways 28, 38 and 40, respectively.

Slidable in the bore 45 is a spool valve member 46, the upper end of which is secured by a coupling 48 to the core of the Bowden cable 18. To vary the effect on the control valve 20 of movement of the lever 17, the sheathing or outer casing of the Bowden cable is provided with a conventional adjusting means in the form of a threaded adjustable coupling 49. Rotation of the coupling varies the effective length of the cable whereby the operative position (Fig. 2) of the spool valve 46 may be adjusted relatively to the bore 45. A

return spring 50 is compressed between the adjustable coupling 49 and the coupling 48.

Enlarged heads 51, 53 on the spool valve 46 are formed to have a sliding, fluid tight fit within the bore 54. Separating the enlarged portions 51 and 53 and slidably mounting a sleeve member or floating piston 52 is a central spindle 54 of lesser diameter than the portions 51 and 53. The floating piston 52, which is of the same diameter as the enlarged portions 51 and 53, normally floats between two springs 56 and 57 of similar strength positioned one on either side of the member 52 and compressed against the enlarged portions 51 and 53. These springs normally maintain the sleeve member 52 midway along the spindle 54 between the enlarged portions 51 and 53, as seen in Fig. 3. Longitudinal grooves or bleed passageways 58 formed in the floating piston 52 provide communication between two main valve spaces 60 and 62, defined respectively as the space between the floating piston 52 and the enlarged portion 51 and the space between the floating piston 52 and the enlarged portion 53.

The relief valve 42 is mounted on the valve block 26 in communication with the passageway 40 and is a sensitive, nevertheless, conventional type comprising a valve body 64 in which there is disposed a movable needle valve plunger 66 having a conical face 67 urged by a spring 68 toward a valve seat 69 formed on the valve body 64. The compression of the spring 68, and hence the opening pressure of the relief valve 42, is preset by an adjusting screw 70 threaded in the valve body 64 and maintained in adjusted position by a lock nut 72. The interior of the relief valve 42 communicates with the reservoir 21 through relief ports 74.

The mechanism operates in the following manner. In its normal or inoperative position, the spool valve member 46 occupies the position shown in Fig. 3, whereby the floating piston 52 floats between the springs 56, 57 midway along the spindle 54. The passageways 33 are unblocked whereby the conduit 16 is in communication with the pump 24. The passageways 35 are likewise unblocked so that the space 60 is in communication with the interior of the reservoir 21. Thus, fluid displaced by the pump 24 from the reservoir circulates through the pipe 32, the valve space 60 and back to the reservoir without producing an appreciable pressure rise in the space 60. Consequently, the fluid pressure in the clamping cylinder 15 which communicates with the space 60 does not rise sufficiently to move the clamp 14 into clamping position. A return spring in the clamping cylinder 15 (not shown) displaces the clamp 14 away from clamping position.

When it is desired to produce a clamping effect at the jack 10 by moving the clamp 14 toward the clamp 12, the hand lever 17 is displaced toward the cylinder 15, which, through the Bowden cable 18, displaces the spool valve member 46 upwardly from the Fig. 3 or inoperative position. When the valve 46 is initially moved, the slidable floating piston 52 is raised along with it and continues to occupy a central position on the spindle 54 such that the passageways 35 are completely blocked. In this position the space 60 does not communicate with the reservoir 21 and the pressure rises in the space 60 and hence within the clamping cylinder 15 with which it communicates. When the pressure in the cylinder 15 has risen sufficiently to overcome the force of the return spring in the cylinder, the clamp 14 is displaced and is maintained in clamping position until the hand lever 17 is released whereupon the spring 50 returns the valve member 46 to its normal inoperative position as just described with reference to Fig. 3.

Again with reference to Fig. 2, as the pressure increases in the space 60, so does the pressure in the space 62 below the floating piston 52. This is because the spaces are in communication by way of the grooves or bleed passageways 58. When this pressure reaches

that at which the relief valve 42 is set to operate, the movable needle valve plunger 66 is displaced and the pressure within the space 62 is relieved due to the flow through the passageways 37, 40, and 74. This fluid is replaced by fluid flowing through the grooves or bleed passageways 58 from the space 60, equilibrium flow conditions being reached when the pressure in the space 62 has diminished to a value just above that required to maintain the relief valve 42 in open condition. Should the pressure in the space 62 drop below this value for any reason, the relief valve 42 will close permitting the pressure again to build up until it is sufficient to open the valve.

As will be seen, a greater area of the conical face 67 of the needle valve plunger 66 is subjected to fluid pressure in the passageway 40, and hence in the space 62, when the valve is opened rather than when it is seated in the seat 69. Consequently, when the valve is open, a smaller pressure in the space 62 can overcome the compressive force of the spring 68 than when the valve is closed. Hence, the closing pressure is less than the opening pressure.

The drop in pressure in the space 62 resulting from the opening of the relief valve 42 produces a differential pressure across the sleeve member 52 which, as a result, is displaced downwardly of the spindle 54 and the sleeve 44, additionally compressing the spring 57 and permitting the spring 56 to expand somewhat. This continues until the forces of the combined spring and fluid pressure acting downwardly upon the sleeve member 52 are in equilibrium with those acting upwardly.

The valve 20 is so designed and adjusted by means of the screw adjustment 70 that when equilibrium conditions have been attained, the floating piston 52 will float with its upper edge partially unblocking the passageways 35. In this condition there is relief flow from the space 60 which prevents the pressure in that space and hence in the clamping cylinder 15 from rising above the desired maximum value. In other words, the pressure in the clamping cylinder 15 is controlled by the volume of the space 60 which communicates with it.

The bleed or flow through the grooves 58 is merely sufficient to maintain the relief valve 42 slightly open, handling a small flow and in a very sensitive condition. In this sensitive condition the relief valve 42 is able to exercise a very stable control, over the equilibrium pressure in the space 60 and in the clamping cylinder 15 by controlling the differential fluid pressure across the sleeve member 52. This results in a substantially constant clamping pressure on the work. Furthermore, any pressure disturbances in the system are rapidly and automatically corrected and a constant clamping pressure is maintained.

As mentioned above, when the operator releases the lever 17 at the end of the trimming operation the respective parts of the valve 20 are returned to their normal or Fig. 3 positions and the pressure within the clamping cylinder 15 is relieved permitting the work to be removed from the jack.

It will be appreciated that the above-described fluid pressure means are relatively simple in nature and effect not only the operable movement of the work clamping member 14 but also include extremely sensitive pressure control means for insuring that the clamping pressure will be maintained at a substantially constant but not excessive value. Furthermore, the control member for operating the entire system is so conveniently positioned on the machine that the operator is not required to remove a hand from the work or jack to actuate the member, nor is foot treadle operation required.

Having thus described my invention, what I claim as new and desire to secure by Letters Patent of the United States is:

1. In a machine for operating on a shoe part on a last, a tool, a manually operated jack movable toward

and away from the tool, fluid operated means for clamping in the jack a last with part of a shoe attached thereto, a fluid pump for directing pressurized operating fluid to the clamping means, valve means for controlling the pressure of the operating fluid, and manually operated control means mounted on the jack for operating said valve and positioned to be grasped by an operator while operating said jack, said fluid pump and said valve means being located remotely from said jack.

2. In a machine for operating on a shoe part mounted on a last, a tool, a jack for supporting part of a shoe and last for presentation to the tool, fluid operated means for clamping the shoe part and last in the jack, a fluid pump, a valve for controlling the pressure of operating fluid supplied to the clamping means by said pump, and manually operated control means comprising a lever movably mounted on the jack and operatively connected to the control valve, said fluid pump and control valve being located remotely of said jack.

3. In a machine for operating on a shoe part mounted on a last, a tool, a jack for supporting part of a shoe and last for presentation to the tool, fluid operated means for clamping the shoe part and last in the jack, a fluid pump, a valve for controlling the pressure of operating fluid supplied to the clamping means by said pump, manually operated control means comprising a lever movably mounted on the jack and operatively connected to the control valve, said fluid pump and control valve being located remotely of said jack, and adjusting means operatively connected to the control valve to vary the effect on said control valve of movement of said lever.

4. In a machine for operating on a shoe part mounted on a last, a tool, a jack for supporting part of a shoe and last for presentation to the tool, fluid operated means for clamping the shoe part and last in the jack, a fluid pump, a valve for controlling the pressure of operating fluid supplied to the clamping means by said pump, manually operated control means comprising a lever movably mounted on the jack and operatively connected to the control valve, said fluid pump and control valve being located remotely of said jack, and adjusting means operatively connected to the control valve to vary the effect on said control valve of movement of said lever.

5. In a machine for operating on a shoe part mounted on a last, a tool, a jack for supporting part of a shoe and last for presentation to the tool, fluid operated means for clamping the shoe part and last in the jack, a fluid pump, a valve for controlling the pressure of operating fluid supplied to the clamping means by said pump comprising a valve cylinder, a piston dividing said cylinder into upper and lower chambers, the fluid pump and the clamping means being at all times in communication with the upper chamber, a fluid relief passageway communicating with the interior of the cylinder, and manually operated control means for shifting the piston from a first position wherein the relief passageway is unblocked and in communication with the upper chamber to a second position wherein the relief passageway is blocked by the piston whereby the pressure in the upper chamber and at said clamping means rises in order to effect a clamping movement.

6. In a machine for operating on a shoe part mounted on a last, a tool, a jack for supporting part of a shoe and last for presentation to the tool, fluid operated means for clamping the shoe part and last in the jack, a fluid pump, a valve for controlling the pressure of operating fluid supplied to the clamping means by said pump comprising a valve cylinder, a piston dividing said cylinder into upper and lower chambers, a passageway through said piston placing said upper and lower chambers in communication, both the fluid pump and the clamping means being at all

times in communication with the upper chamber, a fluid relief passageway communicating with the interior of the cylinder, an adjustable relief valve in communication with the lower chamber for regulating the pressure therein and consequently in said upper chamber and at the clamping means, and means for shifting said piston from a first position wherein the relief passageway is unblocked and in communication with the upper chamber to a second position wherein the relief passageway is blocked by the piston whereby the pressure in the upper chamber and the clamping means rises in order to effect a clamping movement.

7. In a machine for operating on a shoe part mounted on a last, a tool, a jack for supporting part of a shoe and last for presentation to the tool, fluid operated means for clamping the shoe part and last in the jack, a fluid pump, a valve for controlling the pressure of operating

7
fluid supplied to the clamping means by said pump comprising a valve cylinder a piston, dividing said cylinder into upper and lower chambers, a passageway through said piston placing said upper and lower chambers in communication, both the fluid pump and the clamping means being at all times in communication with the upper chamber, a fluid relief passageway communicating with the interior of the cylinder, an adjustable relief valve in communication with the lower chamber for regulating the pressure therein and consequently in said upper chamber and at the clamping means, means for shifting said piston from a first position wherein the relief passageway is unblocked and in communication with the upper chamber to a second position wherein the relief passageway is blocked by the piston whereby the pressure in the upper chamber and the clamping means rises in order to effect a clamping movement, said fluid pump and control valve being located remotely of said jack and said manually operated control means being a lever movably mounted on the jack and operatively connected to the control valve, and adjusting means operatively connected to the control valve to vary the effect on said control valve of movement of said lever.

7. In a machine for operating on a shoe part mounted on a last, a tool, a jack for supporting part of a shoe and last for presentation to the tool, fluid operated means for clamping the shoe part and last in the jack, a fluid pump, a valve for controlling the pressure of operating fluid supplied to the clamping means by said pump comprising a valve cylinder, a floating piston dividing said cylinder into upper and lower chambers, a passageway through said floating piston placing said upper and lower chambers in communication, both the fluid pump and the clamping means being at all times in communication with the upper chamber, a fluid relief passageway communicating with the interior of the cylinder, means for shifting said floating piston from a first position wherein the relief passageway is unblocked and in communication with the upper chamber to a second position wherein the relief passageway is blocked by the piston whereby the pressure in the upper chamber and the clamping means rises in order to effect a clamping movement, an adjustable relief valve in communication with the lower chamber set to open when the pressure therein reaches a predetermined value, whereupon fluid is relieved from said lower chamber causing the pressure in the upper chamber to displace the floating piston toward said first position to effect unblocking of said relief passageway to reduce further the pressure in the upper chamber and at the clamping means.

8. In a machine for operating on a shoe part mounted on a last, a tool, a jack for supporting part of a shoe and last for presentation to the tool, fluid operated means for clamping the shoe part and last in the jack, a fluid pump, a valve for controlling the pressure of operating

5 fluid supplied to the clamping means by said pump comprising a spool valve member slidable in the cylinder and having upper and lower piston heads joined by a spindle, a floating piston on said spindle dividing said cylinder into upper and lower chambers, springs of equal strength in the valve cylinder compressed between said floating piston and said piston heads, the fluid pump and the clamping means being at all times in communication with the upper chamber, a fluid relief passageway communicating with the interior of said valve cylinder, means for shifting the spool valve member from a first position wherein the relief passageway is unblocked and in communication with the upper chamber to a second position wherein said relief passageway is blocked by the floating piston whereby the pressure in the upper chamber and at the clamping means rises in order to effect a clamping movement.

9. In a machine for operating on a shoe part mounted on a last, a tool, a jack for supporting part of a shoe and last for presentation to the tool, fluid operated means for clamping the shoe part and last in the jack, a fluid pump, a valve for controlling the pressure of operating fluid supplied to the clamping means by said pump comprising a spool valve member slidable in the cylinder having upper and lower piston heads joined by a spindle, a floating piston on said spindle dividing said cylinder into upper and lower chambers, a passageway through said floating piston placing said upper and lower chambers in communication, springs of equal strength in the valve cylinder between said floating piston and said piston heads, the fluid pump and the clamping means being at all times in communication with the upper chamber, a fluid relief passageway communicating with the interior of said valve cylinder, means for shifting the spool valve member from a first position wherein the relief passageway is unblocked and in communication with the upper chamber to a second position wherein said relief passageway is blocked by the floating piston whereby the pressure in the upper chamber and at the clamping means rises in order to effect a clamping movement, an adjustable relief valve 20 in communication with the lower chamber set to open when the pressure therein reaches a predetermined value, whereupon fluid is relieved from said lower chamber causing the pressure in the upper chamber to displace the floating piston toward said first position to effect unblocking of said relief passageway to reduce further the pressure in the upper chamber and at the clamping means.
